CLAIM

The ornamental design for notary stamp physical unclonable function reader frame, as shown and described.

DESCRIPTION

FIG. 1 is a front, top, and right side perspective view of a notary stamp physical unclonable function reader frame showing our new design;

FIG. 2 is a rear, bottom, and left side perspective view thereof;

FIG. 3 is front elevation view thereof;

FIG. 4 is a bottom plan view thereof;

FIG. 5 is a rear elevation view thereof;

FIG. 6 is a top plan view thereof;

FIG. 7 is a left side elevation view thereof; and,

FIG. 8 is a right side elevation view thereof.

The broken ones depict the bounds of the claimed design and form no part of the claimed design.

1 Claim, 6 Drawing Sheets
